UNITED STATES PATENT OFFICE.

WALTER E. RATHBUN, OF MILAN, ILLINOIS.

DRIVE FOR CREAM-SEPARATORS.

1,383,854.

Specification of Letters Patent.

Patented July 5, 1921.

Application filed May 7, 1920. Serial No. 379,553.

To all whom it may concern:

Be it known that I, WALTER E. RATHBUN, a citizen of the United States, residing at Milan, in the county of Rock Island and State of Illinois, have invented certain new and useful Improvements in Drives for Cream-Separators, of which the following is a specification.

The present invention has to do with certain improvements in driving mechanism particularly for use in driving centrifugal cream separators. The features of the present invention are very well adapted for use in connection with cream separator drives of the type disclosed in Letters Patent of the United States No. 1,281,418, issued to me under date of October 15, 1918. In order that the features of the present invention may be more easily understood and their mode of operation more readily explained, I have illustrated said features as applied to a construction very similar in form to that illustrated in the aforesaid Letters Patent of the United States. Nevertheless, I wish it clearly understood that I do not limit the use and application of the features of the present invention to the particular construction illustrated and disclosed in the said earlier Letters Patent except as I may do so in the claims.

Bearing the foregoing in mind, Figure 1 shows in perspective a view of a simple form of cream separator having applied thereto a power drive embodying the features of the present invention;

Fig. 2 shows a back face view of the power driving arm and associated parts;

Fig. 3 shows a cross section partly in elevation of the construction shown in Fig. 2;

Fig. 4 shows an enlarged detail section of the driving connection between the pulley and the pinion shaft;

Fig. 5 shows a cross section taken on the line 5—5 of Fig. 4, looking in the direction of the arrows;

Fig. 6 shows a section taken on the line 6—6 of Fig. 4, looking in the direction of the arrows;

Fig. 7 shows a section taken on the line 7—7 of Fig. 6, looking in the direction of the arrows; and

Fig. 8 shows a modified type of drive wheels in which the use of grooved pulleys has been substituted for the use of toothed gears.

Referring first to Fig. 1, the separator

therein indicated is designated in its entirety by the numeral 10. It includes a main shaft 11 which communicates with the rotating bowls through a train of gearing contained within the stand 12. Inasmuch as I am not particularly concerned with the construction of the separator or this train of gearing, I will not further describe these features. Suffice it to state that the shaft 11 is the main shaft on which the power is to be applied.

Ordinarily a crank is applied to the main shaft 11 when the shaft is to be driven by hand power. In order to permit of the use of the present device either by hand or power, I have provided a crank 13 having a handle 14. The construction of these parts is shown in detail in Figs. 2 to 7 inclusive. The crank is provided on its inner end with a hub 15 mounted on a sleeve 16, which sleeve in turn may be set onto the end of the shaft 11 and drivingly secured thereto. A set screw 17 may be provided for securing the sleeve to the shaft 11 in a driving fashion.

When the cream separator is to be driven by hand, this may be done through the medium of the handle 14. In those cases, however, in which it is desired to use a power drive, the instrumentalities which I will now describe may be brought into operation.

For this purpose a gear 18 is drivingly mounted upon the sleeve 16 as by means of a key or the like. In some cases a sleeve or collar 19 may be set onto the end of the sleeve 16 so as to overlie the hub portion of the gear 18, the set screw 17 passing through the collar 19 and serving to hold said collar in position as well as to effect the driving connection onto the shaft 11.

A pinion shaft 20 is journaled in the handle 13 and carries a pinion 21 which in turn meshes with the gear 18. In the modified construction shown in Fig. 8, the use of toothed elements is dispensed with, a friction drive including the friction pulley 22, and the friction pinion 23 being substituted for the toothed gear 18 and toothed pinion 21.

It will be evident that by driving the pinion shaft 20 as by means of a pulley 24 while holding the handle 13 substantially stationary, the cream separator will be driven. In Fig. 1, I have illustrated a belt 25 driving the pulley 24, and the handle 13 is held more or less stationary by a link 26, including a spring 27.

It will be evident that in order to make

use of the pulley 24, a driving connection must be established between said pulley and the shaft 20. It will also be evident that in case the pulley 24 were to be permanently secured to the shaft 20 in a driving fashion, said pulley and the pinion shaft 20 would rotate backward upon turning the crank 13 by hand, so that the shaft 11 of the cream separator would not be driven.

10 I have, therefore, provided means for effecting a driving connection between the pulley 24 and the shaft 20 when it is desired to drive the separator by power and for properly locking the shaft 20 against rotation with respect to the handle 13 when it is desired to drive by hand. I will now describe these means more in detail, and for this purpose reference may be had particularly to Figs. 4, 5, 6, and 7.

20 A collar 28 is secured to the shaft 20 as by means of a pin 29, the pulley 24 being rotatably mounted on the end portion of the shaft 20, and said end portion may be provided with an enlarged head 30 for retaining the pulley 24 in position thereon. The shaft 20 extends clear through the handle 13 within which it is journaled and through the pinion 21, and a nut 31 on its inner end serves to retain all of the elements in position on the shaft 20.

25 An arcuate slot 32 is provided on the outer face of the collar 28, and a pin 33 is slidably mounted within a recess or pocket in the hub of the pulley 24 and is normally spring-pressed outwardly by a spring 34 in said pocket. One end of the slot 32 is slanted or beveled, so that the shaft 20 may, in some cases, run ahead of the pulley 24, but upon driving the pulley 24 in the normal 30 driving direction, the pin 33 will engage the other end of the slot and drive the collar 28.

Another pin 35 is slidably mounted in a pocket in the hub portion of the handle 13, and this pin is normally spring-pressed outwardly by means of a spring 36. An arcuate slot 37 is provided in the back face of the collar 28, into which slot the pin 35 is normally projected by means of the spring 36. One end of the slot 37 is beveled or slanted 40 in such fashion that the shaft 20 and collar 28 may run ahead of the handle 13 when the machine is being power driven, but the arrangement is such that when driving by hand the pin 35 will engage the other end of the slot 37 so as to effect a driving connection and prevent the shaft 20 from rotating in the journal or bearing in the handle 13.

It will be evident that in the normal power drive by the use of the pulley 24, the 45 collar 28 will continue to run ahead of the pin 35, so that each time the pulley 24 completed a rotation the pin 35 would naturally snap back into the slot 37 with a clicking noise. In order to prevent this objectionable

operation, I have provided means whereby 65 the pin 35 may be temporarily disengaged from the collar 28 and locked into such disengaged position. This means comprises a slot 38 through which extends a finger piece 70 39 from the pin 35, and the inner end of said slot 38 is hooked as at 40 to accommodate the handle 39 when the pin 35 has been retracted. By the construction described I have provided, in effect, a ratchet mechanism which serves adequately to fulfil all 75 the requirements of this invention.

In certain constructions now in common use the hand crank 13 is attached to one end of the drive shaft while the gear 18 and pinion 21 are located at its opposite end, but my invention is equally adaptable to such a construction without substantial modification. While I have herein shown and described only certain embodiments of the features of my present invention, still it will be understood that I do not limit myself to the said features except as I may do so in the claims.

I claim:

1. The combination with the operating 90 mechanism of a cream separator including an operating shaft, of a main gear drivingly connected to said shaft, a crank arm pivotally mounted with respect to the shaft, a pinion shaft journaled in the crank arm, a 95 pinion on the pinion shaft drivingly engaging the main gear, a collar drivingly secured to the pinion shaft, a pulley journaled on the pinion shaft adjacent to one face of the collar, a ratchet and pin connection between the pulley and collar permitting the pinion shaft and collar to run ahead of the pulley but insuring a driving connection from the pulley to the pinion shaft when the pulley tends to run ahead of the pinion shaft, and 100 a pin and ratchet connection between the other face of the collar and the crank arm permitting the collar and pinion shaft to run ahead of the crank arm, but preventing a retrogressive movement between these 105 parts, substantially as described.

2. The combination with the operating mechanism of a cream separator including a driving shaft, of a crank arm pivotally mounted concentrically with respect to the 115 driving shaft, a pinion shaft journaled in the crank arm, a gear and pinion connection between the pinion shaft and the driving shaft, a collar secured to the pinion shaft, a pulley journaled on the pinion shaft adjacent to one face of said collar, means in conjunction with the collar and pulley permitting the pinion shaft and collar to run ahead of the pulley, but insuring a driving connection from the pulley to the collar and pinion shaft in the same direction, and 120 means in conjunction with the collar and crank arm permitting the pinion shaft and 125

collar to run ahead of the crank arm, but preventing a retrogressive movement between these parts, substantially as described.

3. The combination with the operating mechanism of a cream separator including a driving shaft, of a crank arm pivotally mounted with respect to the driving shaft, a pinion shaft journaled in the crank arm, a pinion and gear connection between the 10 pinion shaft and the driving shaft, a pulley journaled on the pinion shaft, means in conjunction with the pulley and pinion shaft permitting the pinion shaft to run ahead of the pulley but insuring a driving connection from the pulley to the pinion shaft in the same direction, and means in conjunction with the pinion shaft and crank arm permitting the pinion shaft to run ahead of the crank arm, but preventing retrogressive 15 movement between these parts, substantially as described.

4. The combination with the operating mechanism of a cream separator including

a driving shaft and a pinion shaft, of a crank arm pivotally mounted with respect 25 to the driving shaft, a pinion and gear connection between the pinion shaft and the driving shaft, a pulley on the pinion shaft, and means in conjunction with the pinion shaft and pulley permitting the pinion shaft 30 to run ahead of the pulley but insuring a driving connection from the pulley to the pinion shaft, substantially as described.

5. The combination with the operating mechanism of a cream separator, including 35 a driving shaft and a pinion shaft, of a crank arm operatively mounted with respect to the driving shaft, a driving connection between the pinion shaft and the driving shaft, a pulley on the pinion shaft, and means as- 40 sociated with the pinion shaft and pulley permitting the former to run ahead of the latter but insuring the driving connection from the latter to the former, substantially as described.

WALTER E. RATHBUN.
